UNITED STATES PATENT OFFICE.

PETER M. KLING, OF LACONIA, NEW HAMPSHIRE, ASSIGNEE TO LACONIA CAR COMPANY, OF LACONIA, NEW HAMPSHIRE, A CORPORATION OF MASSACHUSETTS.

UNDERFRAME FOR RAILWAY-CARS.

1,128,331.

Specification of Letters Patent. Patented Feb. 16, 1915.

Application filed July 16, 1914. Serial No. 551,401.

To all whom it may concern:

Be it known that I, PETER M. KLING, a citizen of the United States, and resident of Laconia, in the county of Belknap and State 5 of New Hampshire, have invented new and useful Improvements in Underframes for Railway-Cars, of which the following is a specification.

This invention relates to railway cars and 10 more particularly to cars having a wooden underframe.

The object of the invention is to provide 15 a simple, strong and rigid underframe adapted to carry the draft rigging and which will effectively withstand the violent 20 buffing shocks and pulling stresses to which cars are subjected in service.

The greatly increased use by railroads 25 generally of heavy steel cars and the tendency toward cars of larger capacity and longer and heavier trains, has resulted in greatly increasing the severe buffing and pulling stresses to which cars are subjected, with the result that the wooden cars, in 30 the past universally used and still extensively used, become strained and otherwise damaged, necessitating strengthening and extensive repairs, particularly of the center sills, which carry the draft rigging and are therefore subjected to the severest 35 strains. In strengthening and repairing these cars it has been a common practice to remove the wooden center sills to which the draft rigging is secured and substitute 40 therefor steel sills. This method of repair has proved in practice necessarily destructive to many parts of the car, particularly the floor and underframe thereof, expensive in cost of labor and material, and otherwise unsatisfactory.

It is the object of this invention to 45 provide a construction particularly adapted for use in the repair of wooden cars which have been damaged by buff- 50 ing shocks or other service strains, but which may be advantageously used in new as well as in repair construction. In practising my invention the usual wooden center sills are left intact, but are reinforced in 55 their position with a steel reinforcing frame instead of being removed and replaced by steel center sills as is the usual method at present employed.

In the accompanying drawings which 60 illustrate one embodiment of the inven-

tion,--Figure 1 is a plan view showing parts of the steel reinforcement of a car underframe containing the invention, the wooden parts of the underframe being shown in dotted lines; Fig. 2 is a cross section, on 60 an enlarged scale, through the underframe and draft rigging; Fig. 3 is an end elevation of the lower part of the car body and frame; Fig. 4 is a longitudinal vertical section at one end of the underframe, taken 65 between the center sills; and Fig. 5 is a longitudinal horizontal section on line 5—5 of Fig. 4, showing certain parts of the underframe in plan.

Referring to the drawings, A, A, are the 70 wooden center sills to which the floor B is secured in the usual manner. Extending substantially the entire length of said wooden center sills and suitably secured thereto as by bolts C, are steel or iron reinforcing bars 75 or beams C, preferably Z-bars as shown, the lower flanges of which, c', extend under the wooden sills A (Fig. 2). Abutting against the vertical web of said Z-bars are angle iron or steel bars D secured to said Z-bars 80 by rivets d passing through said webs and having flanges d' extending outwardly from said sills and parallel to the upper flanges c' of said Z-bars. The draft sills E carrying the draft rigging indicated generally 85 at Y, which may be of any suitable type, are secured to said turned flanges c' of said Z-bars and to said angle flanges d' as by rivets e, e', the sills E having suitable recesses e' for the rivet heads as clearly 90 shown in Fig. 2.

F is the bolster, provided with a bolster plate F', secured to said Z-bars.

G is the wooden end sill and H the buffer block between which extends part of the 95 end sheathing I of the car. Suitable fastening means, such as the bolts J, pass completely through and secure the end sill G and buffer block H; and the draft sills E are secured to said buffer block as by bolts 100 W. A fastening member consisting of the angle bar K secured to said draft sills E is anchored between said end sill and said buffer block and secures the same in place. The center sills A are provided with cross- 105 wise tie straps L spaced at intervals; and the usual needle bars M are secured to the longitudinal sills and carry the truss rods N. These straps L, tying the reinforced center sills together, in addition to the end 110

sills, bolsters and needle beam ties, still further increase the strength and rigidity of the structure and insure the united effort of the four center members,—the two wooden center sills and their two steel reinforcements—in withstanding the buffing and pulling stresses in a wooden car.

With the above described construction wooden cars can be effectively repaired and strengthened without tearing out the wooden center sills, thus eliminating the injury to the underframe and the car incidental to removing said center sills. Among other advantages may be mentioned the saving in the cost of both labor and materials by reason of the utilizing of the wooden center sills, the saving of taking them down, the lessening of the destruction of the floor and underframe, the saving of nailing strips for the floor, which must be supplied if steel beams are substituted for the wooden center sills, and reducing the weight of the steel members by approximately six hundred pounds, still retaining the same strength in the underframe, by using lighter steel reinforcing frames bolted to the wooden center sills, in place of the heavier all steel center sills heretofore used for this purpose. Furthermore, this method makes it possible to use the old draft rigging and couplers, which are taken off the cars when all steel center sills are substituted for the wood sills; this results in a substantial saving in cost.

While Z bars are well adapted for the reinforcing of the center sills, other forms of bars may be advantageously used. Furthermore, this construction affords far greater rigidity and strength in the underframe than is obtained by the use of all steel center sills, and thus adapts it the better to withstand the buffing strain or compression as well as the pulling strains. The center members naturally receive the greatest strains, and this structure possesses not only the strength of the wooden center sills, but of the longitudinal steel reinforcements, and the cross ties L, which insure the combined support of the four center members, as well as the reinforcement of the needle beam ties which connect all the longitudinal sills. Moreover, the buffer blocks and sills, bolsters, and needle beams are all fastened together by being fastened to the steel reinforcing frame which extends from end to end of the car.

This structure affords an exceptionally rigid and strong construction, adapted to withstand the severe stresses incidental to modern railway service, which can be readily applied to either old or new cars having wooden underframes, and which is not only cheaper but better than structures where the

wooden center sills are replaced by steel beams.

65

I claim:

1. A reinforced wooden underframe for railway cars, comprising wooden center sills, and metal reinforcing bars secured to said center sills and extending substantially from end to end thereof, each reinforcing bar having a vertical web and a horizontal flange, the vertical web of each bar being secured to the side of, and the flange extending underneath, its center sill, and a series of metal cross ties rigidly connecting said reinforcing bars.

70

2. A reinforced wooden underframe for railway cars, comprising wooden center sills, and metal reinforcing sills, and metal reinforcing bars secured to said center sills and extending substantially from end to end thereof, each reinforcing bar consisting of a Z-bar, the vertical web of which is secured to the sides of its center sill, and the lower flange of which extends underneath its center sill, while the upper flange extends laterally from the side of its center sill.

75

3. A reinforced wooden underframe for railway cars, comprising wooden center sills, and metal reinforcing bars secured to said center sills and extending substantially from end to end thereof, each reinforcing bar consisting of a Z-bar, the vertical web of which is secured to the outer side of its center sill, and the lower flange of which extends inward underneath its center sill, while the upper flange extends laterally outward from the side of its center sill.

80

4. A reinforced wooden underframe for railway cars, comprising wooden center sills, and metal reinforcing bars secured to said center sills and extending substantially from end to end thereof, each reinforcing bar having a vertical web and a horizontal flange, the vertical web of each bar being secured to the outer side of, and the flange extending inward underneath, its center sill, an angle bar secured to the side of the vertical web of each reinforcing bar near the end, with its flange extending outwardly opposite the flange of the reinforcing bar which is underneath the center sill, draft sills comprising each a horizontal flange and vertical web, said horizontal flanges of the draft sills being secured to the under sides of the flanges underneath the center sills and also to the under sides of the flanges of said angle bars.
